UNITED STATES PATENT OFFICE

1,978,158

VACUUM CLEANER

Henry A. Kroenlein, Cleveland, Ohio, assignor to
 Electric Vacuum Cleaner Company, Inc., Cleve-
 land, Ohio, a corporation of New York

Original application October 11, 1932, Serial No.
 637,242. Divided and this application June 15,
 1933, Serial No. 675,888

8 Claims. (Cl. 15—8)

The present application is a division of my application, Serial No. 637,242, filed October 11, 1932.

The principal objection made by users of vacuum cleaners in households is the noise they make. The noise is due in large part to the high speed of the motor and fan and to the vibrations incident thereto, such vibrations being caused wholly or largely by the lack of absolute dynamic balance.

10 My invention has for its object the provision of a resilient mounting for the motor and fan to the end that the vibrations thereof will not be transmitted to the supporting base, and to the provision of resilient sealing means between the 15 fan chamber and the motor housing.

For a consideration of what I believe to be novel and my invention, attention is directed to the accompanying description and the claims appended thereto.

20 In the drawing which is illustrative of my invention, Fig. 1 is a view partly in section and partly in elevation of my improved cleaner; Fig. 2 is a fragmentary view of the motor supporting ring; Fig. 3 is a sectional view of one of the cushions, and Fig. 4 is a detail sectional view of part 25 of a sealing ring.

4 indicates the base or floor piece of the cleaner which is cast in one piece of aluminum or other light weight material. Its walls are thick enough 30 so as to be not readily set into vibration by the air flowing through the passages therein. In the front is a nozzle 5 having front and rear lips 6 and 7. In the rear of the base is an outlet conduit 8 to receive the dirt filtering bag or other 35 separating device. 9 indicates a partition which divides the base into two chambered parts. The lower chamber is in direct communication with the nozzle 5 and the upper chamber contains the suction fan 10 and opens into the outlet conduit 8.

40 The base has an inturned cylindrical flange 11 forming a support for a high speed electric driving motor 12 and the fan. The fan is mounted on the lower end of the shaft of the motor and carries a pulley 13 for driving a brush 14 located 45 in the nozzle, by means of a quarter turned belt 15. Below the belt is an opening to permit access to the belt and which is normally closed by a cover 16. The upper end of the motor is enclosed by a thin sheet metal casing or housing 17 having suitable ventilating openings 18 in the rear wall thereof. The housing is secured in place by suitable screws which are angularly spaced and is separated from the motor by a relatively large 50 radial clearance to provide space for the cushion supports for the motor.

To reduce the noise incident to operation of the cleaner, the motor and fan are first dynamically balanced as accurately as possible, having due regard for the cost of such an operation. They are then mounted on the cleaner by an 60 elastic or cushioned suspension. For this purpose, the lower end of the motor casing is provided with an outwardly extending flange 20 of relatively large diameter and mounted thereon are numerous soft rubber cushions 21 of tubular form and angularly spaced, each being made in two parts as shown in Fig. 3, said parts having a shoulder between them. The lower end of each tube is seated in a metal cup 22 which holds it centrally in place about a stud 23 which is screw- 65 threaded into the flange 20. The upper end of each stud is shouldered to receive a spacing washer 24 which is of a size and shape to center the upper end of the tube. Each stud is separated from the wall of the cushion by a large radial 70 clearance which arrangement increases the flexibility of the mounting, especially when the motor tends to rock on its support. Above the washers and common thereto is a large thin metal ring 25 and supported thereby is a soft rubber ring 26 75 of a diameter greater than that of the ring 25. Above the rubber ring is a second thin metal ring 27. The upper end of each of the several studs is screw-threaded and provided with a nut whereby the rings and washer are securely clamped in 80 place. The rubber ring 26 is of such outside diameter as to engage a substantial surface on the wall of the outer casing or housing 17 and thus maintain contact at all times. As shown, the peripheral edge of the rubber ring is curved downwardly and fits into a curved portion of said housing while the wall defining the bore of the ring engages the cylindrical casing of the motor 12. The metal rings 25 and 27 being common to all 85 of the studs 23 serve to support them at their upper ends. The soft rubber ring 26 serves to prevent circulation of air currents between the regions above and below it. It also prevents contact between the metal parts supporting the motor and the housing 17 which would give rise to noise 90 upon vibration of the parts.

To support the motor and fan through the medium of the rubber cushions, a thin metal ring 28 is employed having a bore which is substantially larger than the motor casing to prevent metal to 105 metal contact. The peripheral edge of the ring 28 is seated on the inturned flange 11 of the base. The ring has as many holes 29 as there are cushions, said holes being smaller in diameter than the cushions. The shoulder 30 on each of the upper 110

cushion members is of a diameter to snugly fit said holes and also to fit into the shouldered recess in the lower member of the cushion. It will be observed that whereas the lower wall of the 5 fan chamber is defined by the partition 9, the upper wall is defined by the motor and the supporting parts therefor.

Because the housing 17 is open to the atmosphere through the ventilating openings 18, it is 10 necessary to shut off the space or chamber between the wall of the housing and the casing of the motor from the fan chamber, and also to prevent dust, etc., from entering the motor casing through its ventilating openings. Furthermore, 15 it is necessary to prevent any vibrations of the motor and fan from being transmitted to the base of the machine. To accomplish this, a molded ring 31 of soft rubber is provided. The upper end of the ring has an outwardly extending flange 20 which rests on flange 11 of the base and the lower end has a rounded bead 32 which is seated in a corresponding groove in the flanged lower end 20 of the motor casing. In the manufacture of 25 rubber rings 31, difficulty was experienced in properly aligning the holes for the retaining screws with those in the flange 11 of the housing. In other words, although the mold had accurately spaced screw holes, the resulting product did not. This difficulty was finally overcome by using a 30 steel insert 33 in the flange 34 of the rubber ring, Fig. 4. The insert is in the form of a thin metal ring having as many openings as there are retaining screws. The bead 32 and groove in the flange 20 are so related that the bead tightly 35 encloses the metal wall in which the groove is formed, thereby making a tight connection at this point to prevent air leakage and also the passage of fine dust into the motor. Because the 40 molded ring 31 is made of soft rubber, it offers no appreciable resistance to vibratory movements of the motor in any direction, and due to its elasticity or yielding nature, prevents the transmission of motor and fan vibrations to the base which 45 would be the case if the ring were of rigid material.

What I claim as new and desire to secure by Letters Patent of the United States is:

1. A vacuum cleaner comprising a base having an inturned flange and containing a fan chamber, a nozzle communicating therewith, a fan in the chamber, a motor for rotating the fan having a flanged casing, a cushioning support for the motor and fan comprising a thin metal ring supported at its periphery by the inturned flange 50 of the base, a plurality of elastic tubular elements carried by the ring and located on opposite sides thereof, studs secured to the flange on the motor casing, means on the upper ends of the studs for securing the elements in place, and an elastic 55 sealing means between the base and said motor flange.

2. A vacuum cleaner comprising a base containing a fan chamber, a nozzle communicating therewith, a fan in the chamber, a discharge conduit, a motor for rotating the fan, having a 60 flanged casing, a housing for the motor casing supported by the base and spaced from the motor, a perforated metal ring also supported by the base, elastic elements supported by the ring and 65 extending on opposite sides thereof, studs for securing the elements to the flange on the motor casing, a second metal ring resting on the ends of the elements remote from the flange to which ends of the studs are secured, and a ring of elastic 70 material supported by the studs and engaging

the inner wall of the housing for preventing contact between the second ring and the housing.

3. A vacuum cleaner comprising a flanged base 80 containing a fan chamber, a nozzle communicating therewith, a discharge conduit for the chamber, a fan in the chamber, a motor for rotating the fan, means interposed between the flange on the base and the motor for elastically supporting the latter, and an elastic sealing ring between a part of the motor and the base, said ring having a part engaging the motor, a flange resting on that of the base, and a metal insert molded within said flange.

4. A vacuum cleaner comprising a base having an inturned flange and containing a fan chamber, said flange having angularly spaced openings to receive retaining screws, a nozzle receiving dust laden air and delivering it to the chamber, a discharge conduit for the chamber, a fan in the chamber, a motor for rotating the fan, means resting on the flange for elastically supporting the motor, and an elastic sealing ring which with the motor defines one wall of the fan chamber, said ring having a part engaging the motor, a flange resting on that of the base, and a metal insert molded within the flange, said flange and insert having angularly spaced openings which register with those in the flange of the base.

5. A vacuum cleaner comprising a base containing a fan chamber, a nozzle communicating therewith, a discharge conduit for the chamber, a fan in the chamber, a motor for rotating the fan, having a flanged casing, a housing for the motor in spaced relation thereto and supported by the base, a metal ring also supported by the base, elastic elements supported by the ring and extending on opposite sides thereof, studs which extend through the elements and are seated in the flange of the motor casing, and an elastic sealing ring having a flange at one end resting on the base 105 and clamped in place by the metal ring and at its lower end closely fitting the flange on the motor casing to prevent the flow of dust laden air into the housing.

6. A vacuum cleaner comprising a base containing a fan chamber, a nozzle communicating therewith, a fan in the chamber, a discharge conduit, a motor for rotating the fan having a flanged casing, a housing for the motor in spaced 110 relation thereto and supported by the base, a cushioning means carried by the base for supporting the motor and fan and preventing the transmission of vibrations thereof to the casing, an elastic seal between the base and the motor 115 casing, and a second elastic seal between the housing and the motor casing.

7. A vacuum cleaner comprising a base having a flange and containing a fan chamber, a nozzle, an outlet for the chamber, an electric driving motor for the fan having a supporting flange, and a cushioning support for sustaining the weight of the motor, comprising a thin metal ring attached to the flange of the base and separated from the motor by a radial clearance, a plurality of hollow 120 elastic elements, each having a pair of members, one of which is situated on one side of the ring and the other on the opposite side and seated on the motor flange, a stud extending through each pair of members which is secured to the 125 motor flange and is separated from the inner wall of said members by a relatively large radial clearance, spacing means for each member carried by the end of the stud remote from the motor flange and a flexible member which en- 130

gages a part of the motor casing and the base and defines a part of the fan chamber.

8. A vacuum cleaner comprising a chambered base, a fan, a motor for driving the fan, a housing separated from the motor by a radial clearance and having ventilating openings, an elastic suspension for the motor carried by the base, an elastic sealing means between the motor and

housing, and a second elastic sealing means between one end of the motor and the base which also defines a part of a chamber for the fan, said sealing means both cooperating to prevent dust laden air from the fan chamber passing outwardly through the ventilating openings in the housing.
